A technical drawing of a component. It features a rectangular base with a central vertical slot. Above this base is a hatched rectangular section. A curved line labeled 'AC' connects the top of the base to the hatched section. The label '30' is positioned above the top edge of the base, and the label '78' is positioned below the base.

UNITED STATES PATENT OFFICE.

KARL F. RANGER, OF DETROIT, MICHIGAN.

UNIVERSAL JOINT.

1,271,615.

Specification of Letters Patent.

Patented July 9, 1918.

Application filed May 10, 1916. Serial No. 96,475.

To all whom it may concern:

Be it known that I, KARL F. RANGER, a citizen of the United States, and residing at Detroit, in the county of Wayne and State of Michigan, have invented a new and Improved Universal Joint, of which the following is a specification.

The present invention relates to universal joints, and its objects are to provide a construction wherein the members may be more readily manufactured and assembled and wherein more strength is secured than heretofore; to provide, in combination with elements for lubricating a universal joint from a source internal to the joint itself, a non-liquid-tight casing whereby the power transmitting elements are concealed and whereby mud and other foreign objects are excluded; to provide improvements in a casing for universal joints; and also to improve the joint with reference to the details of the lubricating features. The invention will be more fully understood upon reference to the following description and to the appended drawings, in which:

Figure 1 is a fragmentary longitudinal section through one embodiment. Fig. 2 is a section of a slightly modified construction on a line corresponding to the line 2-2 of Fig. 1, the cross or connecting element of the joint being removed. Fig. 3 is a longitudinal section showing one manner in which the yoked or bifurcated member may be constructed to receive the cross. Fig. 4 is a fragmentary longitudinal section through a modification. Fig. 5 is a section on the line 5-5 of Fig. 4. Fig. 6 is a side view showing another embodiment. Fig. 7 is a plan view corresponding to Fig. 6. Fig. 8 is a perspective view of the casing shown in Figs. 6 and 7. Fig. 9 is a plan view of one of the blanks from which this casing is made.

Similar reference characters refer to like parts.

The main shaft sections which are to be joined are designated 1 and 2; it will be observed that the former is provided with the end flange 3 from the outer face of which a flange 4, preferably annular, projects toward the other main section. Inclosed by this flange and conforming closely thereto is the annular shoulder 5 of a divided cross-pin receiving section of lug suction, the individual members 6 and 8 of which are provided with an appropriate male and female meeting surface or surfaces 9 whereby, when

the members are properly positioned within the flange 5, they are prevented from moving laterally in respect to each other in one direction, it being understood that the flange takes the primary stresses tending to withdraw the male member from the female member. The parts 6-8 and 1 are prevented from being displaced longitudinally in respect to one another by rivets or bolts 10.

Rigid with the members 6 and 8 are lugs 12, preferably bossed at 13, in which are formed alined sockets for the reception of 70 bushings or other suitable bearings 14 wherein the journals 15 of the cross-member 16 may turn. It will be seen that the member 16 has flanges or shoulders 17 which overlap the bushings 14 and exclude dirt. 75 The outer end of both sockets may be closed by the walls 18 (Fig. 2) or but one socket may have a wall of this nature, the other being closed by a screw plug 19 (Fig. 1), or both walls may be replaced by plugs. The embodiment shown in Fig. 1 is, however, preferable since it allows the cross-member, which is provided with a longitudinal passage 20 that extends from end to end, to be readily filled with lubricant, the latter being 85 thrown into the ends of the passage by centrifugal force and gradually distributed to the bearings. This construction is also preferable in that it allows line reaming of the sockets for the bushings 14.

The cross-member 16 is pierced at right angles to its length and receives a second cross-member 21 (also having a longitudinal passage 22 in communication with the passage 20) which is secured to the member 16 95 by a pin 23. These members, taken together, form the "cross"; and the ends of the member 21 are received in sockets (Fig. 3) formed in the divided end 26 of the member 2, the outer end of one of the sockets 100 being closed by a wall 28 and the other by a plug 29, through which lubricant may, of course, be admitted, bushings or other bearings 30 being preferably interposed between the members 2 and 21.

The member 2 may, if desired, be provided with a circular flange 32, the outer surface 33 of which is an element of a sphere having its center at the intersection of the members 16 and 21, or in other words, at the point about which the members 1 and 2 have relative universal movement. A sheet metal casing (shown in dashed lines in Fig. 1) having a spherical portion 36 that con-

2

forms to the surface 33 and a cylindrical base portion 37 which is secured to the members 6-8 in any preferred manner may be used to protect and conceal the parts, and since the oil is retained in the bearings in the manner described above, it follows that the fitting of the portion 36 to the surface 33, need not be accurate. For manufacturing reasons, it is, however, preferred to employ the casing shown in full lines (Fig. 1), which consists in a cylindrical body 38 (secured to the compound member 3-6-8 in any suitable way) together with the perforated inner and outer dished or flanged end plates 39 and 40 (between which is formed the annular transverse slot 41) in which the perforated annular plate 42 slides in accordance with the relative movements of the casing and the member 2. If desired, a fiber washer 43 may be interposed between the parts 2 and 42 to prevent rattling.

In the modification which appears in Figs. 4 and 5, the cross-members 43' and 44, which correspond to the members 16-21, are made solid, and the end wall 18 and plug 19 shown in Fig. 1 are omitted, likewise the wall 28 and plug 29 of the member 2, as well as the flange 32. Lubricant must therefore be applied externally, and in order to retain it and to exclude dust a casing member 46 (similar to the member 36-38) is employed, together with a second sheet metal casing member having a spherical end 49 received within the end of the member 46. The second member also includes a cylindrical portion 50 spaced from the shaft 2, a portion 51 conforming closely thereto, and a connecting wall 52 by which a chamber is formed for packing 53, which is held in place by the follower ring 54 and spring 55. In this construction the shafts 1 and 2 (shown hollow) are closed in any suitable way.

In the modification shown in Figs. 6 to 9, inclusive, the same driving elements are employed as in Figs. 1 and 2, but the casing is divided circumferentially into two duplicate sections each of which includes a base flange 60 that is secured to the circumferentially adjacent edges of the lugs 12 by screws 61. At points adjacent the lugs the casing sections are offset outwardly therefrom and extended circumferentially in the opposite direction from the lugs to a point a slight distance beyond the nearest edge of the adjacent division of the arm 26 of the member 2 to form spherical elements 62; thus the end 63 of the element 62 is removed from the adjacent edge 64 of the other casing member somewhat less than the transverse circumferential dimension of the corresponding lug 12. Each of the casing members is formed by stamping a blank of the shape indicated in Fig. 9 in an obvious manner.

65 Since it is desirable to make the joints

particularly in motor vehicle propeller shafts, of the least possible external dimensions, the plates 6-8 are preferably provided with depressions 65, as shown in Fig. 5, which afford clearance for the divisions 70 of the end 26 of the member 2.

Using other nomenclature and the same numerals, the joint may be regarded as including a shaft member 1 having a head 3 and furcations 6-8 detachably secured to said head by the bolts 10, said furcations having complementary base portions provided with an annular shoulder 5 engaging said head. There is also present a hollow cross member 16 having integral journals 15 on one of the cross-arms thereof, a hollow journal pin 21 insertible through the other cross-arm, a bifurcated shaft member 2 having a recess in one of its furcations for receiving the hollow journal pin 21 and an aperture in the opposite furcation (Fig. 3) through which said pin is inserted, and a cap 29 for closing said aperture after the insertion of said pin.

It is clear that various modifications of 90 the several features, other than those shown, may be made without departing from the spirit of my invention; for example, instead of the "cross" shown, the well known substitute in the form of a "ring" may be 95 employed. It is also obvious that the pivotal axes of the joint may in some cases be spaced longitudinally from each other along the general line of the shafting; in other words, the "cross" may be extended longitudinally along the line of shafting, in which event it may be formed of two or more rigidly connected sections, each of which forms a portion of the length of the cross. The flange 4 may also be replaced 100 by lugs or short sections at points intermediate the ends of the dividing line between the members 6 and 8. I do not, therefore, 105 wish to be limited other than as indicated by the subjoined claims.

110 I claim:—

1. A universal joint comprising two main members and a connecting member through which stress is transmitted, a section interposed between one of the main members and the connecting member, said section having aligned bearing elements the common axis of which is at right angles to the length of said main member, said section being formed of male and female members whose dividing line extends in general at an angle to said axis, the last mentioned main member having rigid therewith means whereby the male and female members are prevented from separating from one another by relative movement at an angle to the dividing line.

115 2. A universal joint comprising two main members and a connecting member through which stress is transmitted, a section inter-

- posed between one of the main members and the connecting member, said section having alined bearing elements the common axis of which is at right angles to the length of 5 said main member, said section being formed of male and female members whose dividing line extends in general at an angle to said axis, the last mentioned main member having rigid therewith means whereby the 10 male and female members are prevented from separating from one another by relative movement at an angle to the dividing line, and additional means for preventing the section from moving longitudinally relative to the last mentioned main member.
- 15 3. A universal joint comprising two main members and a connecting member through which stress is transmitted, a section interposed between one of the main members and 20 the connecting member, said section having alined bearing elements the common axis of which is at right angles to the length of said main member, said section being formed of a plurality of members, the last mentioned 25 main member being socketed to receive the ends of the plurality of members, and conforming to said ends whereby said members are prevented from spreading in a plane at an angle to the axis of said last mentioned 30 main member, the connecting member and the interposed section being of such relative cross-section as to prevent the former from being wholly removed from the latter while said interposed section is received in the 35 socket in the main member.
4. A universal joint comprising two main members and a connecting member through which stress is transmitted, a section interposed between one of the main members and 40 the connecting member, said section having alined bearing elements the common axis of which is at right angles to the length of said main member, said section being formed of male and female members whose dividing 45 line extends in general at an angle to said axis, the last mentioned main member having rigid therewith means whereby the male and female members are prevented from separating from one another by relative 50 movement in any direction except at right angles to the plane of said connecting member.
5. A universal joint comprising two main members and a connecting member through 55 which stress is transmitted, a section interposed between one of the main members and the connecting member, said section having alined bearing elements the common axis of which is at right angles to the length of said 60 main member, said section being formed of a plurality of parts, the last mentioned main member having rigid therewith means whereby the section is prevented from moving laterally in respect thereto, the connecting member and the interposed section being 65 of such relative cross-section as to prevent disengagement from one another while said interposed section is in engagement with the means whereby it is prevented from moving laterally. 70
6. A universal joint comprising two main members and a connecting member through which stress is transmitted, a section interposed between one of the main members and the connecting member, said section having 75 alined bearing elements the common axis of which is at right angles to the length of said main member, said section being formed of a plurality of parts, the last mentioned main member having rigid therewith means 80 whereby the section is prevented from moving laterally in respect thereto, and additional means for preventing relative longitudinal movement of the section and last mentioned main member, the connecting 85 member and the interposed section being of such relative cross-section as to prevent disengagement from one another while said interposed section is in engagement with the means whereby it is prevented from moving 90 laterally.
7. A pivotal joint including two members, and a split section rigid with one of the members and interposed between it and the other member, the member with which the 95 split section is rigid having a circumferential flange embracing said split section to prevent the latter from shifting laterally, the second member having alined ends pivotally mounted respectively in the corresponding 100 portions of the split section, the split section and the second member being of such relative cross-section that the latter is not removable from the former while the split section is rigid with the member by which it 105 is carried.
8. A universal joint comprising two main members and a connecting member in the form of a cross through which stress is transmitted, a section interposed between 110 one of the main members and the cross, said section being formed of male and female members whose dividing line extends in a general direction at right angles to the length of the adjacent main member, the 115 members of the section including lugs having alined perforations in which the end portions of one of the arms of the cross are received, the axis of said perforations being at an angle to said dividing line, the other main member being bifurcated adjacent the cross and receiving the ends of the other arm of the cross; the first mentioned main member having rigid therewith means for preventing separation of the members of the 120 section. 125
9. A universal joint comprising two main members and a connecting member in the form of a cross through which stress is transmitted, a section interposed between 130

one of the main members and the cross, said section being formed of male and female members whose dividing line extends in a general direction at right angles to the length of the adjacent main member, the members of the section including lugs having alined perforations in which the end portions of one of the arms of the cross are received, the axis of said perforations being at an angle to said dividing line, the other main member being bifurcated adjacent the cross and receiving the ends of the other arm of the cross, the first mentioned main member having rigid therewith means for preventing separation of the members of the section, and bearings interposed between the ends of the arms of the cross and the members in which they are received.

10. A universal joint comprising two main members and a connecting member in the form of a cross through which stress is transmitted, a section interposed between one of the main members and the cross, said section being formed of male and female members whose dividing line extends in a general direction at right angles to the length of the adjacent main member, the members of the section including lugs having alined perforations in which the end portions of one of the arms of the cross are received, the axis of said perforations being at an angle to said dividing line, said cross being hollow to receive lubricant and the outer ends of said lugs being closed to prevent the escape of the lubricant, the first mentioned main member having rigid therewith means for preventing separation of the members of the section.

11. A universal joint comprising two main members and a closed hollow connecting member through which stress is transmitted, a section interposed between one of the main members and the connecting member, said section being formed of male and female members whose dividing line extends transversely of the adjacent main member, the members of the section being in pivotal co-operative relation with the connecting member, the axis of the pivots being alined and at an angle to the dividing line, the first mentioned main member having rigid therewith means for preventing separation of the members of the section.

12. A universal joint having means for lubricating the several bearing surfaces thereof from a common source within the joint, and a casing whereby the joint is concealed, said common source of lubricant being within the casing and divided from the rest of the chamber inclosed by said casing.

13. A universal joint having two main members and a closed hollow connecting member in pivotal relation to the main members wherein lubricant is stored and whereby it is fed to the bearing surfaces of all

of the pivots and a casing whereby the connecting member is concealed.

14. A universal joint having means for lubricating the several bearing surfaces thereof from a common source within the joint, and a casing whereby the joint is concealed, said casing allowing the escape of liquids from the interior thereof.

15. A universal joint having two main members and a closed hollow connecting member in pivotal relation to the main members wherein lubricant is stored and whereby it is fed to the bearing surfaces of the pivots and a casing whereby the connecting member is concealed, said casing allowing the escape of liquids from the interior thereof.

16. A universal joint comprising two main members and a connecting member through which stress is transmitted, a split section interposed between one of the main members and the connecting member, said last mentioned main member having integral therewith means whereby the parts of the split section are prevented from spreading, said split section having alined bearing elements opening toward each other and receiving projections on the connecting member, said connecting member being hollow and with the ends of the bearing elements affording chambers for lubricant for the bearings.

17. A universal joint comprising two main members and a connecting member through which stress is transmitted, a split section interposed between one of the main members and the connecting member, said last mentioned main member having integral therewith means whereby the parts of the split section are prevented from spreading, said split section having alined bearing elements opening toward each other, the outer end of one of the bearing elements being formed integral with the corresponding portion of the split section, said bearing elements receiving projections on the connecting member, said connecting member being hollow and with the ends of the bearing elements affording chambers for lubricant for the bearings.

18. A universal joint comprising two main members and a connecting member through which stress is transmitted, a split section interposed between one of the main members and the connecting member, said last mentioned main member having integral therewith means whereby the parts of the split section are prevented from spreading, said split section having alined bearing elements opening toward each other, the outer end of one of the bearing elements being formed integral with the corresponding portion of the split section, a detachable closure for the outer end of the other bearing element, said bearing elements receiving projections on the connecting member, said connecting member

being hollow and with the ends of the bearing elements affording chambers for lubricant for the bearings.

19. A universal joint comprising two main members and a connecting member through which stress is transmitted, a split section interposed between one of the main members and the connecting member, said last mentioned main member having integral therewith a circumferential flange whereby the parts of the split section are prevented from spreading, said split section having aligned bearing elements opening toward each other, and said connecting members including aligned projections, immovable in respect to each other, received in the bearing elements.

20. In a universal joint, a shaft member provided with a head, furcations separately detachably secured to said head and having complementary base portions provided with an annular shoulder engaging with said head.

21. In a universal joint, a hollow cross member having integral journal bearings on one of the cross-arms thereof, a hollow journal pin insertible through the other cross-arm, a bifurcated shaft member having a recess in one of its furcations for receiving said hollow journal pin and an aperture in the opposite furcation through which said pin is inserted, a cap for closing said aperture after the insertion of said pin, a complementary bifurcated shaft member, provided with detachable furcations separately engageable with the integral journals of said cross member and closed at their outer ends, and means for positioning and securing said detachable furcations to their shaft member.

22. In a universal joint, the combination with a cross member having integral journals on one of its cross-arms, of a journal detachably engaging the other of said cross-arms, a bifurcated shaft member having integral furcations, one of said furcations being recessed to receive said journal pin and the opposite furcation being apertured for the insertion of said pin, a complementary bifurcated shaft member having detachable furcations recessed to engage said integral journals and provided with complementary portions of a circular head, a circular head integral with the shaft member recessed to receive the complementary circular portions of said furcations, and clamping means for securing said heads to each other.

23. In a universal joint, a shaft member provided with a head, furcations secured to said head, said furcations including shoulders extending concentrically about the axis of the shaft member through which shoulders stresses tending to spread the furca-

tions apart in a plane perpendicular to the axis of the shaft member are transmitted. 65

24. In a universal joint, a shaft member provided with a head, furcations separately detachably secured to said head and having complementary base portions provided with an annular shoulder through which stresses tending to spread the furcations apart in a plane perpendicular to the axis of the shaft member are transmitted. 70

25. In a universal joint, a shaft member provided with a head, furcations separately detachably secured to said head and provided with complementary base portions having an annular shoulder engagement with said head, and means for accurately peripherally positioning said base portions 80 upon said head.

26. In a universal joint, a hollow cross member having integral journal bearings on one of the cross-arms thereof, a hollow journal pin insertible through the other cross-arm, a bifurcated shaft member having a recess in one of its furcations for receiving said hollow journal pin and an aperture in the opposite furcation through which said pin is inserted, a cap for closing said aperture after the insertion of said pin, a complementary bifurcated shaft member, provided with detachable furcations separately engageable with the integral journals of said cross member and closed at their outer ends, and means for positioning and securing said detachable furcations to their shaft member. 95

27. In a universal joint, the combination with a cross member having integral journals on one of its cross-arms, of a journal detachably engaging the other of said cross arms, a bifurcated shaft member having integral furcations, one of said furcations being recessed to receive said journal pin and the opposite furcation being apertured for the insertion of said pin, a complementary bifurcated shaft member having detachable furcations recessed to engage said integral journals and provided with complementary portions of a circular head, a circular head integral with the shaft member recessed to receive the complementary circular portions of said furcations, and clamping means for securing said heads to each other. 100

28. In a universal joint, a hollow cross member, complementary bifurcated shaft members having recesses in the furcations thereof forming journal bearings for said cross member, a hollow pin insertible through an aperture in one of said furcations for connecting said cross member thereto, the interior of said pin having communication with the interior of said cross member, and a cap for closing the aperture through which said pin is inserted. 110 120 125
